Patented Jan. 20, 1920.

INVENTOR.
Walter E. Taft.

UNITED STATES PATENT OFFICE.

WALTER EVERETT TAFT, OF PROVIDENCE, RHODE ISLAND, ASSIGNOR TO THE ASSOCIATE COMPANY, OF BOSTON, MASSACHUSETTS, A CORPORATION OF MASSACHUSETTS.

SPARK-PLUG FOR INTERNAL-COMBUSTION ENGINES.

1,328,463.

Specification of Letters Patent. Patented Jan. 20, 1920.

Application filed March 6, 1917. Serial No. 152,863.

To all whom it may concern:

Be it known that I, WALTER EVERETT TAFT, a citizen of the United States, residing at Providence, in the county of Providence and State of Rhode Island, have invented certain new and useful Improvements in Spark-Plugs for Internal-Combustion Engines, of which the following is a specification.

10 This invention relates to improvements in spark-plugs for use in internal combustion engines and the object of my improvement is to produce a spark-plug in which the liability of short circuiting by carbon, oil or 15 soot, is reduced to a minimum, and incidentally simplicity of construction and economy of manufacture in attaining the result mentioned.

In the accompanying drawing:

20 Figure 1 is a side elevation partially in section of a spark-plug involving my invention.

Fig. 2 is a plan view of the same.

25 Fig. 3 represents a sectional view of the sparking end taken on the line 2—2 of Fig. 2 and on the line 4—4 of Fig. 4.

Fig. 4 represents a view of the under side of the inside washer shown in Fig. 3.

Fig. 5 is a sectional view, corresponding 30 to Fig. 3 of a modified arrangement of the washers used for the outer electrode.

Fig. 6 is a plan view of the plug with the conducting wire at one side of the center of the hole in the electrode.

35 Fig. 7 is another modification showing a different arrangement of the washers for the outer electrode.

My improved spark-plug comprises a body 1 inclosing a chamber 2, is provided 40 with a suitable insulating structure 3, and has for the electrodes the straight, axially positioned wire 4 for the inner electrode and for the outer, coöperating electrode a washer-like structure composed as shown of 45 a pair of washers placed face to face, respectively a top or outer washer 5 and an inner washer 6.

The washers 5 and 6 are concentric with the wire 4, the said wire passing entirely 50 through the holes in the said washers, the diameter of the wall of the said holes being somewhat larger than the diameter of the wire so that the said wall is in spaced relation to the wire.

The walls of the holes 7 and 8 in the individual washers 5 and 6 are of counter-sunk or beveled form, and the washers are placed together with the larger ends of the holes adjacent or opposed one to the other, the two washers as a unit being rigidly held in position, which is at the sparking end of the spark-plug structure. Accordingly the border wall of the opening that is opposed to the wire 4 as a whole is in the form of a pair of inwardly projecting annular ribs having a V-shaped form of cross-section and formed by the edge portions at the smaller ends of the holes in the individual washers, and these ribs are separated by a recess of appreciable depth and width, the depth being due to the inclination of the bevel and the width at the tips corresponding to the combined thickness of the two washers.

As shown, washers 5 and 6 are alike.

In some cases I may have the hole in the individual washers of slightly different diameter, the one with the smaller diameter serving as the active electrode or electrode proper.

In Fig. 5 an additional washer 6' is shown below to the washers 5 and 6, being otherwise arranged as described above.

In Fig. 6 the wire electrode 4 is shown to one side of the center of the outer electrode 5.

In Fig. 7 the washers 5 and 6 are placed with the beveled side walls of the holes directed in the same direction, the large end of the hole in one being opposed to the small end of the hole in the other.

Other arrangements of the washers may be also used, it being important to avoid any arrangement that would interfere with providing a sharp edge for the active portion.

The said sharp edge or rib serves most effectively for sparking with high potential and at the same time tends to remain clean because of the absence of a seat to which foul particles can adhere.

The provision of a plurality of ribs with the intervening recess provides a restricted passage of non-uniform cross-section, that has a choking effect on the gases bearing foul matter and foreign particles so that the flow of such gases in and out of the chamber 2 is retarded or checked, and the tendency to foul and become short circuited is reduced to a minimum.

Such flow of gases is a surging effect due to the impulses of the explosive mixture in the cylinder and has a tendency if unrestricted to deposit short-circuiting material 5 on the electrodes.

- The gap between the inner, insulated electrode 4, of wire, and the outer, grounded electrode formed by the washers 5 and 6 is relatively small, so that it would be difficult 10 and essentially impracticable to provide the peculiar form for the wall of the opening in the grounded electrode, such as described, in a unitary structure, whereas by the expedient of using a plurality of separate washers, 15 each individually provided with a hole having a simple beveled wall, and placed together to make a composite structure, the desired condition for proper operation is conveniently obtained.
- 20 Thus a non-cylindrical form of cross-section is provided for the wall of the said opening, which may be designated as wavy, or undulating, or corrugated, and the same is built up of elements having the border 25 wall for the opening of simple form, being divergent relatively to the axis continuously in one direction.

I claim as my invention:—

1. In a spark plug, comprising a pair of 30 electrodes for coöperating one with the other, one of the said electrodes being in the form of a straight wire, and axially positioned in the spark plug structure, the other of the said electrodes consisting of a washer-

like structure having an opening through 35 which the said wire extends, the walls of the said opening opposed to the said wire being in spaced relation to the said wire, the said walls being in the form of a plurality of inwardly projecting annular ribs having a 40 V-shaped cross-section, the adjacent ribs being separated by a recess of appreciable width and depth, and the said washer-like structure being composed of a plurality of washers each of which has a hole with beveled side walls.

2. A spark-plug comprising an insulated electrode of wire and a grounded electrode having an opening concentric with the said wire, the said opening being of relatively 45 small diameter so that the wall of the said opening is separated from the said wire by a relatively small gap, the said wall of the opening being of non-cylindrical form of 50 cross-section, comprising sharp, flange-like portions at the ends, connected by a relatively deep valley or recess, and the said grounded electrode being built up of a pair of washers, each of the said washers having a beveled border wall for the opening, and the two washers being placed together with the faces corresponding to the larger ends of the washer openings opposed and in 55 abutment.

WALTER EVERETT TAFT.
